Primary Examiner — Michelle E. Wilson*Assistant Examiner* — Ania Aman(74) *Attorney, Agent, or Firm* — Schwegman Lundberg & Woessner, P.A.(57) **CLAIM**

I claim, the ornamental design for a fluid transportation device with directed cooling, as shown and described.

DESCRIPTION

FIG. 1 is a top-left-perspective view of our fluid transportation device with directed cooling showing my new design; FIG. 2 is a top-left-perspective view of our fluid transportation device with directed cooling;

FIG. 3 is a back view thereof;

FIG. 4 is a front view thereof;

FIG. 5 is a right-side view thereof;

FIG. 6 is a left-side view thereof;

FIG. 7 is a top view thereof; and,

FIG. 8 is a bottom view thereof.

In FIG. 1, the broken lines depict unclaimed subject matter only and form no part of the claimed design.
